UNITED STATES PATENT OFFICE.

ALVA L. KITSELMAN, OF RIDGEVILLE, INDIANA.

WIRE-FABRIC MACHINE.

SPECIFICATION forming part of Letters Patent No. 592,931, dated November 2, 1897.

Application filed July 22, 1896. Serial No. 600,149. (No model.)

To all whom it may concern:

Be it known that I, ALVA L. KITSELMAN, a citizen of the United States, residing at Ridgeville, in the county of Randolph and State of Indiana, have invented a new and useful 5 Wire-Fabric Machine, of which the following is a specification.

This invention relates to wire-fabric machines.

10 The main and primary object of the present invention is to effect certain improvements in machines for weaving wire fabric, especially for fencing purposes, whereby the same shall be entirely automatic in character to provide 15 for the twisting of the weft-wires together or onto the line's wires, and also for the transferring or shifting of the spool-carrying devices from one twister-wheel to another.

19 The invention also contemplates improved 20 means for propelling the machine with accuracy and despatch, whereby the mesh of the fabric being woven may be varied at will, according to the character of the work, and as a 25 general object it is the intention to provide 25 a wire-fabric machine constructed in such a manner that all of the parts thereof may be readily assembled and replaced without the services of a skilled mechanic.

With these and many other objects in view 30 the invention consists in the novel construction, combination, and arrangement of parts hereinafter more fully described, illustrated, and claimed.

In the drawings, Figure 1 is a side elevation 35 of a wire-fabric machine constructed in accordance with this invention. Fig. 2 is a front elevation thereof. Fig. 3 is a rear elevation. Fig. 4 is a central vertical sectional view of the entire machine and its propelling mechanism. Fig. 5 is a vertical sectional view of the machine in rear of the twister-wheels on the line 5 5 of Fig. 4. Fig. 5^a is an enlarged detail elevation of a portion of the 40 front side of the machine, showing more clearly the relative arrangement of the twister-wheels, the spool-carriers, the guide plates or castings, and the switch points or fingers. Fig. 6 is a similar view to Fig. 5^a, showing the switch-points in a reversed position and the spool-carriers transferred to different twister-wheels. Fig. 7 is a similar view to Fig. 6, with the spool-carriers, the guide

plates or castings, and the switch points or fingers removed. Fig. 8 is an enlarged detail sectional view of one of the complete twisting 55 devices of the machine comprising one of the stationary hollow spindles and one of the twister-wheels, with the several attachments and parts carried thereby. Fig. 9 is a detail cross-sectional view on the line 9 9 of Fig. 6, 60 showing the engagement of the elliptical retaining-plates of the spool-carriers with the inner guide-flange of the guide plates or castings. Fig. 10 is a detail in perspective of one of the spool-carriers. Fig. 11 is a similar view 65 of one of the spool-carriers with its spool removed. Fig. 12 is a detail plan view of the combined tension and locking plate for the spool. Fig. 13 is a detail in perspective of the separate removable bearing-bushing for each twister- 70 wheel. Fig. 14 is an enlarged detail vertical sectional view of that portion of the machine having the mechanism for automatically operating the switch points or fingers. Fig. 15 is a detail elevation of the cam device for intermittently operating the switch points or fingers. Fig. 16 is a detail top plan view of the ratchet-propelling device to the machine. Fig. 17 is a vertical sectional view on the line 17 17 of Fig. 16. Fig. 18 is a detail in perspective of 80 the clamp-plate for the propelling device having the adjustable stop-pin regulating the mesh of the fabric. Fig. 19 is a vertical sectional view on the line 19 19 of Fig. 16. Fig. 20 is a similar view on the line 20 20 of Fig. 85 16. Fig. 21 is a detail in perspective of one of the gear twister-wheels. Fig. 22 is a detail enlarged view of the locking device for each of the hollow stationary spindles. Fig. 23 is an enlarged detail sectional view of the 90 guide plate or casting forming the pivotal support for a switch point or finger. Fig. 24 is a detail in perspective of the guide plate or casting illustrated in section in Fig. 23. Fig. 25 is a detail in perspective of the form of guide 95 plate or casting alternating with the form illustrated in Fig. 24. Fig. 26 is a detail in perspective of the guide plate or casting used at the top and bottom of the machine in connection with the uppermost and lowermost twister-wheels. Fig. 27 is an enlarged detail sectional view of a modified form of the hollow 100 stationary spindle employed for stringing a barbed line-wire therethrough. Fig. 28 is an

enlarged detail elevation of the catch device for the beveled gear drive-pinion.

Referring to the accompanying drawings, the numeral 1 designates an upright frame-board of a suitable height, according to the height or width of fabric or fencing to be woven by the machine, and said upright frame-board 1 is supported for travel over the ground at its lower end on the opposite parallel base-plates 2. The base-plates 2 are arranged at opposite side edges of the upright frame-board 1 and are provided near one end with short upwardly-disposed arm extensions 3, which are pivotally secured to the side edges of the frame-board on pivot screws or bolts 4, which permit the plates 2 to be moved at an inclination to the upright disposition of the frame-board. Immediately above the pivotal support 4 of the base-plates 2 the arm extensions 3 are provided with segmental slots 5, receiving the clamping-bolts 6, mounted in the frame-board 1 and providing means for rigidly clamping the base-plates 2 stationary when adjusted. The base-plates 2 project beyond the front and rear sides of the upright frame-board 1, and the portions of said plates in front of the frame-board are somewhat longer than their rear portions, so as to steady the machine as it advances along the line of fencing or fabric being woven, and at the opposite extremities of the said base-plates 2 the latter are provided with short inwardly-disposed bearing-axles 7, on which are mounted the ground wheels or rollers 8, which support the machine for travel over the ground.

In connection with the wheeled support of the machine is preferably employed a ground-track 9, (illustrated in Fig. 2 of the drawings,) and which may consist of ordinary planking, and by reason of the adjustability of the wheeled base-plates 2 it will be obvious that such plates may be adjusted to suit the inclination of the ground without affecting the desired vertical disposition of the frame-board, which is quite an important feature in connection with wire fencing or fabric machines.

The upright frame-board 1 is provided therein with a series of vertically-aligned regularly-spaced openings 10, in which are detachably fitted one end of the hollow vertically-aligned stationary spindles 11. The hollow vertically-aligned stationary spindles 11 are arranged in a number equal to the greatest number of warp or line wires in connection with which the machine can be used, and each of said spindles 11 is provided in opposite sides, near one end, with the diametrically opposite notches 12, adapted to receive therein the opposite parallel side portions 13 of an open locking-key 14. The open locking-key 14 for each stationary spindle is substantially rectangular in form and is provided at one end with a circular portion 15 sufficiently large to be readily slipped over the end of the spindle projecting beyond the rear side

of the upright frame-board, and at one side of the circular portion 15 for the remaining portion of its length the locking-key 14 tapers in thickness, so as to form a wedge to tightly fasten the spindle in place. It will be obvious that when the spindle is inserted through the opening 10 therefor, so as to carry its notched end beyond the rear side of the frame-board, the circular portion 15 of the locking-key is slipped over the notched projecting end of the spindle, so as to bring the opposite parallel portions 13 of the key in alignment with the side notches 12, and by moving said side portions 13 of the key into the notches 12 and hammering the key so that it will wedge itself against the frame-board and in the notches 12 the spindle will be drawn tightly to its proper position on the frame-board.

Each of the vertically-aligned stationary spindles 11 is provided intermediate of its ends and at the side of the frame-board opposite the locking-key with an annular bearing shoulder or flange 16, between which and the upright frame-board 1 is arranged a detachable bearing-bushing 17. The detachable bearing-bushing 17 loosely registers on the spindle 11 and bears at one end directly against the shoulder 16, and at its end opposite the shoulder 16 the bearing-bushing 17 is provided with an annular bearing-flange 18, which rests flat against the front side of the upright frame-board 1, and arranged to loosely revolve on the bearing-bushing 17, between the shoulder 16 and the flange 18, is the cylindrical flanged hub 19 of the toothed or gear twister-wheel 20.

In connection with the mounting of the twister-wheel a very important feature to be noted is that the detachable bearing-bushing is a trifle longer than the length of the wheel-hub 19, so that when the locking-key for the spindle is tightened, so as to draw the shoulder 16 against the bushing 17 and the latter against the frame-board 1, it is impossible to bind or wedge the twister-wheel, which will always be sufficiently loose between the flanges 16 and 18, so as to freely revolve on its spindle. This is of especial importance in assembling the parts of the machine together and in dispensing with machine-work in fitting the parts so that the twister-wheels will freely operate.

The locking-keys provide for detachably locking the spindles in place, whereby the same can be readily removed and replaced, and at their outer ends beyond the front side of the machine frame-board 1 the said spindles are provided with the bearing portions 21, which loosely receive thereon the central bearing-collars 22 of the combined guide and supporting disks 23, loosely arranged at the outer end of each spindle. The combined guide and supporting disks 23 have the collars 22 preferably formed integral therewith and projected from one side, so as to loosely engage over the spindles, and at their inner edges the collars 22 are provided with a se-

ries of retaining-tongues 24, which are bent over and loosely engage with an annular bead or rib 25, formed exteriorly on the spindles near their outer ends. The disks 23 are used 5 in connection with the spool-carriers for the purpose of guiding and supporting the outer portions of said carriers, as will be herein-after described; but said disks are provided with central wire-openings 26, communicat- 10 ing with the interior of the spindles and de-signed to receive the longitudinal warp or line wires of the fabric being woven by the machine.

Since each spindle has mounted thereon in 15 the manner described a cogged or gear twister-wheel 20, these wheels are arranged in vertical alinement one above the other and the cogs or teeth of the adjacent wheels mesh, so that the entire series of wheels are geared to- 20 gether for a simultaneous rotation, and one of the intermediate twister-wheels 20 carries at its inner side a beveled gear-wheel 27, meshing with an adjacent beveled gear-pinion 28, mounted on a short drive-shaft 29, 25 journaled in a suitable bearing 30, secured at the rear side of the upright frame-board 1 and having attached to its outer end a crank-handle 31, which is grasped by the hand and turned in a continuous forward direction to 30 provide for the simultaneous turning of all of the twister-wheels, as will be readily understood. Directly above the beveled gear-pinion 28 is arranged a casing or box 32, pro- 35 vided in its outer side with a slot 33 and re- ceiving therein a self-adjusting check-dog 34, provided with a lower beveled end 35, loosely riding over the cogs or teeth of the beveled gear-pinion 28 as the same is turned in a forward direction.

40 The check-dog 34 is raised automatically by the teeth of the pinion and drops between the teeth by gravity; but the lower end of said dog is beveled in a direction so as to ride over the teeth of the pinion only when it turns 45 forward, thereby causing the dog to lock it-self between the teeth of the pinion should the crank-handle be turned in a backward direction. The said self-adjusting catch-dog 34 is provided with an offstanding stop-pin 50 36, working in the slot 33 of the casing 32 and serving to limit the movement of the dog, while at the same time permitting the dog to be lifted out of engagement with the gear-pinion should it be found necessary during the 55 operation of the machine.

The intergeared vertically-alined twister-wheels 20 are of a uniform size and are pro- 60 vided at diametrically opposite points with peripheral notches 37, and at the points where the notches 37 occur the cogs or teeth of the wheels are interrupted to leave spaces for the notches and provide for the proper connection of the spool-carriers 38 with the wheels, so that such wheels during their rotation will 65 positively carry the spool-carriers therewith. The spool-carriers 38 carry the weft or mesh wires, which are twisted together at the points

of intersection or around the longitudinal warp or weft wires, and, as is common in ma-chines of this character, every alternate 70 twister-wheel is active and carries a pair of spool-carriers, excepting, of course, the top and bottom wheels of the series, which at in- 75 tervals carry only one spool-carrier when the weft or mesh wire is being twisted around the top and bottom line-wires of the fabric, all of which is well understood by those skilled in the art.

Each spool-carrier 38 essentially comprises a substantially U-shaped frame-arm 39, pro- 80 vided at one side and at a point intermediate of its ends with an offstanding spool axle or spindle 40 and at one end with a pair of spaced parallel elliptical retaining-plates 41, con- 85 nected together by a short rounded neck-piece 42, which registers in the notches 37 of the twister-wheels to provide a connection be- 90 tween such wheels and the spool-carriers, whereby the latter will be rotated with the wheels. The short neck-piece 42 of each 95 spool-carrier is arranged centrally between the pair of elliptical retaining-plates 41, which are provided with pointed ends 43, and at the end of the frame-arm 39, opposite the retaining-plates 41, each spool-carrier is provided 100 with a circular bearing-head 44, which has a peripheral contact with the loose combined guide and supporting disks 23 at the outer end of the spindle about which the spool-car- 105 rier rotates. The circular bearing-head 44 at one end of each spool-carrier is provided therein with a central wire-guide slot or open- 110 ing 45, and at opposite sides of said slot or opening with separate wire-guide openings 46, all adapted to receive and form guides 115 for the weft or mesh wire b, which is twisted together or onto the warp or line wire a. The weft or mesh wire b is carried in quantities on the wire spools or reels 46^a, mounted to turn on the spool axles or spindles 40 of each 120 spool-carrier, and in connection with the slot 45 and the separate guide-openings 46 in the head 44 of each spool-carrier it is to be ob- 125 served that by passing the weft or mesh wire through the said slot 45 or either of the open- 130 ings 46 the tension of such wire may be partly regulated, according to the character of the work.

The offstanding spool-axe or spindle 40 of each spool-carrier is provided at one end with a squared locking-head 47, from opposite sides of which are projected the short locking-studs 48, which together with the head 47 coöperate with a spring-plate 49, which serves the double function of a spring-tension and locking-plate 125 for the spool 46^a. The spring-plate 49 is bowed in a longitudinal direction and is provided with bent contact ends 50, which have a direct contact with one of the circular flat end heads of the wire-spool 46^a, and at a point interme- 130 diate of its ends the combined tension and locking plate 49 is provided with a central squared opening 51, at diametrically opposite side edges of which opening and communicat-

ing therewith are formed guide-notches 52, which pass over the studs 48 in fitting the plate 49 on the axle 40 and in removing the plate. In adjusting the plate 49, after the 5 wire spool or reel 46^a has been placed on the axle or spindle 40 of the spool-carrier, the said plate 49 is brought to a position with the oppositely-located notches 52 in alinement with the short locking-studs 48. The plate 49 is 10 then passed over the locking-head 47, and by then pressing on the central portion of the plate, so as to force the same toward and against the adjacent spool-head, the squared opening 51 is carried below the plane of the locking-studs 48. With the locking-plate held in this position the same is turned with the spool until brought to a position at direct 15 right angles to the position when first fitted over the axle 40, and when the locking-plate reaches this last position the opening 51 again registers with the squared locking-head 47 and the plate springs out against the inner sides of the studs 48, with the opening 51 engaging over the head 47, thereby locking the 20 plate 49 on the spool-axle 40 and preventing such plate 49 from turning with the spool or reel as the weft-wire is pulled off of the same. When the plate 49 is locked in the position referred to, the same exerts a spring-tension 25 against one side of the spool 46^a, so as to retard the rotation of such spool sufficiently to place the proper tension of the weft or mesh wire wrapped thereon. When it is desired 30 to remove the plate 49, the same is pressed inward out of engagement with the locking-head 47 and turned until the notches 52 aline with the studs 48, as will be readily understood.

The engagement of the short neck-piece 42 of each spool-carrier with the notches 37 of 35 the twister-wheels disposes the elliptical retaining-plates 41 of each carrier, respectively, at the front and rear sides of the twister-wheels, and as thus positioned the said retaining-plates travel in contact with the 40 guide plates or castings 53. The guide plates or castings 53 are substantially V-shaped and are arranged with their apices or points projected into the reentrant spaces formed between the adjacent meshing twister-wheels 45 at opposite sides of such wheels. The said V-shaped plates or castings 53 are provided with the flanged attaching-feet 54, adapted to rest flat against the front side of the upright frame-board 1, and certain of said attaching-feet 54 are preferably provided with the securing-pins 55, cast integrally therewith and engaging in previously-bored openings 56, formed in the front side of the upright frame-board, and it is to be observed that the 50 said pins 55 not only assist in securing the guide plates or castings in position, but also form guides in assembling the parts of the machine together, so as to insure the guide plates or castings being fitted in true positions. Other of the said attaching-feet 54 are provided with screw-openings 57, which

receive the fastening-screws 58 for firmly fastening the guide plates or castings in position.

The V-shaped guide plates or castings 53 essentially comprise an outer segmental base-flange 59 and a main guide-flange 60, projected from the inner side of the base-flange 59, intermediate of its edges and at right angles thereto, and said main guide-flange 60 is provided with a flat bearing-surface 61, arranged parallel with the main base-flange 59, it being observed at this point that the main guide-flange 60 is illustrated in the drawings as being of a substantial T shape, but this formation of the flange is simply for the purpose of imparting lightness to the casting, as it is simply necessary to provide a flange 60, disposed at right angles to the flange 59, so as to project between the pair of spaced retaining-plates 41 of each spool-carrier. 85

The plates or castings 53 are arranged in vertical alinement on opposite sides of the vertically-alined series of twister-wheels and are of a uniform V shape, excepting at the extreme top and bottom of the machine, where 90 for the upper and lowermost twister-wheels of the series is employed a pair of segmental guide plates or castings 53^a, which, excepting for their segmental shape, are of precisely the same construction as the plates or castings 53 95 and serve to complete the circular guideways for the spool-carriers as they are rotated with the said uppermost and lowermost twister-wheels.

Referring more particularly to the circular 100 guideways referred to, it will be noted that the V-shaped guide plates or castings are placed together as closely as possible, so that the segmental side portions of the directly-adjacent guide plates or castings will be arranged in the same circular plane, and thereby 105 practically form continuations of each other, and this arrangement being duplicated at opposite sides of each twister-wheel it will be obvious that a complete circular guideway 110 for the spool-carrier is formed directly adjacent to and around the periphery of each twister-wheel. The elliptical retaining-plates 41 of each carrier are disposed, respectively, at the front and rear sides of the twister- 115 wheel carrying the same, and said retaining-plates are of a sufficient width so as to project beyond the cogged periphery of the twister-wheels and work, respectively, at the opposite sides of the main guide-flanges 60 surrounding the twister-wheel. This disposition of the retaining-plates 41 of each spool-carrier respectively at the front and rear sides of the segmental guide-flanges 60 surrounding the twister-wheel serves to retain or hold the 120 spool-carrier in engagement with the twister-wheel so as to rotate therewith, and it will be further observed at this point that the outer segmental edges of the retaining-plates 41 ride in contact with the outer base-flanges 59, 125 at opposite sides of the main guide-flanges 60, while the short neck-pieces 42 of the spool-

- carriers ride in contact with the flat bearing-surface 61 at the inner edges of the said main guide-flanges 60, thereby completing a bearing-contact of the spool-carriers with the 5 guide plates or castings that serves not only to retain the spool-carriers properly in engagement with the twister-wheels, but also to steady the spool-carriers and insure a positive even running of the machine.
- 10 Every alternate guide plate or casting 53 in each vertical row of such plates or castings is provided with a pivot-collar 63, pivotally receiving the pivot-pin 64 at one end of an oscillatory switch point or finger 65, working at 15 the front side of the guide plate or casting and having at a point intermediate of its ends a connecting-pin 66, working in a segmental slot 67, formed in the plate or casting at one side of the pivot-collar and directly adjacent 20 to the point or apex of the casting. At each side of the vertically-aligned series of twister-wheels the switch points or fingers 65 are arranged to oscillate across the points or apices of every alternate guide plate or casting, and 25 said switch points or fingers are also alternately arranged at opposite sides of the twister-wheel—that is, the opposite switch points or fingers are not mounted in the same horizontal planes, but are diagonally opposite 30 each other, so that in connection with each twister-wheel there is a pair of switch points or fingers arranged, respectively, at diagonally opposite points of the wheel, as clearly illustrated in Figs. 5^a and 6 of the drawings.
- 35 The oscillatory switch points or fingers 65 are tapered toward their inner swinging terminals and are provided with curved side edges 69, so as to readily guide or transfer the spool-carriers from one twister-wheel to 40 another in the manner to be presently described. In connection with the opposite vertical rows of the oscillatory switch points or fingers 65 is employed a pair of opposite vertically-reciprocating operating-bars 70. The 45 vertically-reciprocating operating-bars 70 are respectively arranged at opposite sides of the vertical row of spindles and work in front of the upright frame-board in rear of the twister-wheels and the guide plates or castings, and 50 each of the vertically-reciprocating operating-bars 70 is provided with a series of perforations 71, loosely receiving one end of the connecting-pins 66 of the switch points or fingers in front of such bar. The two vertically-reciprocating operating-bars 70 are respectively pivoted at their upper ends, as at 72, to the opposite extremities of an intermediate connecting-link 73, pivotally mounted intermediate of its ends, as at 74, on the upright 55 frame-board near the upper end thereof and providing means for the simultaneous movement of the operating-bars in opposite directions, whereby all of the switch points or fingers in one vertical row will be oscillated or 60 moved in one direction, while the switch points or fingers in the other vertical row will be simultaneously moved in an opposite direction

to provide for the proper switching or transferring of the spool-carriers from one twister-wheel to another.

70

One of the vertically-reciprocating operating-bars 70 has fixedly secured to the inner side thereof at a point intermediate of its upper and lower ends a substantially rectangular yoke 75, having straight upper and lower sides 76 and opposite curved end portions 77. The yoke 75 has arranged to work inside of the same a cam projection 78 of substantially triangular form and projected from one side of a toothed cam-wheel 79, 80 mounted on the inner end of a short stub-shaft 80, turning in a bearing-opening 81, formed in the upright frame-board 1 and carrying on its outer end at the rear side of the upright frame-board a pointer 82, working in 85 front of a numbered dial-plate 83, circular in shape and fastened on the rear side of the upright frame-board for the purpose to be presently referred to.

The toothed cam-wheel 79 works within a 90 wheel-recess 84, formed in the front side of the upright frame-board, and arranged in said recess in rear of the said wheel 79 is a bowed leaf-spring 85, which draws the pointer 82 firmly against the dial-plate 83 and takes up 95 all slack in the mounting of the shaft 80 and exerts a sufficient friction against the inner side of the wheel 79, so as to prevent the same from turning accidentally and thereby interfering with the operation of the machine. 100 The said cam-wheel 79 is illustrated as being provided with a peripheral series of regularly-spaced strike-teeth 86 and adapted to be engaged by the adjusting-pins 87, projected from the inner side of one of the 105 twister-wheels 20 at diametrically opposite points of the spindle on which said wheel is mounted. By reason of employing a pair of diametrically opposite adjusting-pins 87 the cam-wheel 79 is moved a distance of two of 110 its teeth at each complete revolution of the twister-wheel, and as the cam-wheel is preferably provided with eight strike-teeth 86 it will require four complete revolutions of the twister-wheels to make one complete revolution of the cam-wheel, during which complete revolution of the cam-wheel the switch points or fingers are adjusted twice to provide for 115 two transfers or shifts of the spool-carriers, as will be more particularly referred to. 120

The cam projection 78, carried by the cam-wheel 79, while of substantially triangular form, is provided with a single eccentrically-disposed contact-point 88 and a curved or segmental bearing portion 89, which is concentric with the center of the cam-wheel 79. Assuming the said cam 78 to be in the position illustrated in Fig. 15 of the drawings and traveling in the direction indicated by the arrow, the contact-point 88 will ride against 125 the lower straight side 76 of the yoke 75 and will lower such yoke, together with the operating-bar 70 to which it is fitted, such movement causing an elevation of the opposite op-

erating-bar 70 by reason of the link connection 73. As the wheel 79 continues to turn under the adjusting influence of the pins 87, the segmental portion 89 of the cam projection 78 rides over the lower straight side 76 of the yoke 75 and serves to hold the operating-bars, and consequently the switch-points or fingers, in the position to which they were adjusted by the engagement of the cam with said lower straight side of the yoke 75, and the parts remain in this position until the contact-point of the cam projection reaches the upper straight side 76 of the yoke, when the reverse action or adjustment takes place. By reason of the cam 78 holding the yoke 75 in its elevated and depressed positions for a portion of the time while the cam-wheel 79 is rotated means are provided to allow each pair of spool-carriers to make two complete revolutions with the twister-wheel carrying the same before they are shifted or transferred to the adjacent twister-wheels. This operation insures two complete twists of the weft-wires around the line or warp wires or together before a transfer or shift is made.

The free swinging ends or terminals of the switch points or fingers 65 are thrown by the vertically-reciprocating operating-bars 70 against the front circular guide-flanges 90, formed on the front sides of the twister-wheels and serving in conjunction with the switch points or fingers to properly guide the spool-carriers while being rotated with the twister-wheels and also while transferring or shifting from one wheel to another, and this is important to note in connection with the operation of the machine for weaving a line of fabric, whether for fencing or other purposes. As already referred to, in the operation of the machine every alternate twister-wheel is an active wheel, while the other twister-wheels carry no spool-carriers until the adjacent wheels have made two complete revolutions. Each active wheel, excepting, of course, the uppermost and lowermost, carries in its diametrically opposite notches 37 a pair of spool-carriers which, when rotated with the wheel, pay out the weft or mesh wire as the same is twisted together at the point of intersection or onto the warp or line wires, as is well understood by those skilled in the art, and while the active twister-wheels are rotating with the spool-carriers locked in their notches in the manner already described the switch points or fingers are disposed in such positions as to hold the spool-carriers in place until a shift or transfer is to be made.

With the spool-carriers rotating with each active twister-wheel it will be noted by a reference particularly to Figs. 5^a and 6 of the drawings that the switch points or fingers at diagonally opposite sides of such twister-wheels are disposed in a position with their swinging ends or terminals respectively against the guide-flanges 90 of the twister-wheels above and below the wheel carrying the spool-carriers, so that as the said active

twister-wheel rotates the outer elliptical retaining-plates 41 of the spool-carriers carried thereby strike against the guide-flanges 90 of the adjacent twister-wheels and also ride against the switch points or fingers contacting with such flanges and which deflect the said elliptical retaining-plate onto the segmental guide-flanges 61 immediately surrounding the active twister-wheel. When two complete revolutions of each active twister-wheel are made, the position of the switch-points is reversed, so that when the outer elliptical retaining-plates 41 of the spool-carriers carried by said wheel reach the circular guide-flanges 90 of the adjacent twister-wheels the swinging ends or terminals of the switch points or fingers will be in contact with the front circular guide-flange 90 of the said previously-active wheel, and will deflect the elliptical retaining-plates onto the segmental guide-flanges 61 immediately surrounding the adjacent twister-wheels immediately above and below the previously-active wheel, it being of course understood that as the twister-wheels rotate the notches 37 of such wheels come to a position where they register, so as to receive the short neck-pieces 42 of the spool-carriers.

In connection with the adjustment of the switch points or fingers and the transferring of the spool-carriers the pointer 82 and dial-plate 83 have an important function, it being noted that the dial-plate 83 is provided with numbers corresponding with the number of teeth on the cam-wheel 79, so that the operator turning the crank-handle and facing the rear side of the wheel can tell by glancing at the pointer and dial when a transfer or shift of the spool-carriers is about to be made, so that the machine can be moved along to the desired width of the mesh before another twist is made, it being noted that the pointer and dial would indicate when the switch points or fingers are thrown immediately in advance of the transfer or shift of the spool-carriers from the active to the previously-inactive wheels.

To provide for propelling or advancing the machine and to regulate the size of mesh of the fabric being woven, a propelling device is employed that operates in conjunction with the warp or line wires of the fencing or fabric, and this propelling device essentially comprises a circular drum 91, provided with a peripheral wire groove 92, adapted to receive one complete wrap of the warp or line wire a , so that as the drum 91 is rotated in the manner to be described the machine will pull itself along on the warp or line wire. The rotating drum 91 is provided at its center with oppositely-disposed spindle projections 93, which loosely turn at their tip extremities in the bearing-collars 94, formed at one end of the angled clamp-plates 95, adapted to adjustably embrace opposite side edges of the upright frame-board 1, so as to support the drum 91 for rotation at the rear side of the said frame-board. The drum 91 is mounted

for rotation between the parallel arms 96 of the angled clamp-plates, and adjacent to the angled portions of said plates which embrace the opposite side edges and rear side of the upright frame-board the parallel arm portions 96 of said plates are connected by the clamping-bolts 97, which when tightened serve to rigidly clamp the plates 95 onto the upright frame-board and when loosened allow the clamp-plates and the rotary drum to be adjusted to the desired elevation, according to the height of fabric being woven.

The rotating drum 91 is provided at opposite sides of its vertical center with the opposite internally-toothed ratchet-flanges 98 and 99, respectively, the ratchet-teeth of said flanges 98 and 99 being respectively disposed reversely to each other. The internally-toothed ratchet-flange 98 at one side of the drum 91 is designed to be engaged by the points of a pair of diametrically opposite gravity check-dogs 100, pivotally mounted on the pivot-pins 101 at the inner side of the stationary cap-plate 102, preferably formed on one 25 of the parallel arms 96, supporting the drum and serving as a cap for one side of the drum. The teeth of the opposite internally-toothed ratchet-flange 99 of the drum are designed to be engaged by a pair of diametrically opposite gravity adjusting-dogs 103, pivotally mounted on the pivot-pins 104 at the inner side of a movable cap-plate 105, provided with a bearing-collar 106, loosely turning on one of the spindle projections 93 of the drum 35 and carried at the inner end of a hand-lever 107, which is adjusted up and down to provide for the oscillation of the plate 105 and the consequent movement of the adjusting-dogs 103 over the ratchet-teeth of the flange 99. The gravity adjusting-dogs 103 are preferably provided at one side of their pivotal support with the finger-pins 108, projecting through segmental slots 109, formed in the plate 105, and adapted to be grasped by the 40 fingers of the hand to entirely disengage the points of the dog 103 from the flange 99 for a purpose to be hereinafter described.

The parallel arm 96 opposite the arm having the stationary cap-plate 102 is provided 50 with a circular series of pin-openings 110, adapted to receive an adjustable stop-pin 111, and said openings 110 are numbered on the outside of the arm to indicate the length of the mesh of fabric to be woven, and said adjustable stop-pin 111 is adapted to limit the movement of the hand-lever 107 by engaging with a web or lug 112, formed on one side of the lever 107 and having a play between the movable cap-plate 105 and the adjacent 55 clamp-arm 96, as clearly illustrated in Fig. 16 of the drawings. The arm 96, carrying the adjustable stop-pin 111, is also provided with vertically-aligned diametrically opposite limiting-pins 113, which limit the extreme 60 upward and downward movement of the lever 107, it being noted that the web or lug

112 is also designed to engage against the pins 113.

When it is determined what the size of the mesh of the fabric is to be, the adjustable stop-pin 111 is adjusted in the proper pin-opening 110 according as the mesh is to be a one-inch, two-inch, or other size mesh, and the pin 111 will positively limit the play of the hand-lever 107, so that such play will be fixed 70 and uniform and thereby positively insure the making of a fabric having a uniform mesh. When the hand-lever 107 is moved in one direction, the adjusting-dogs 103 freely travel over the teeth of the ratchet-flange 99, but when the lever is moved in an opposite direction the points of the dogs 103 engage with the teeth of said flange and rotate the drum 91, thereby causing it to travel along the warp or line wire and carry the machine therewith. 80 As the drum 91 is rotated in this manner the points of the check-dogs 100 freely ride over the teeth of the ratchet-flange 98 and engage with the teeth of said flange to positively prevent the drum from slipping back and disturbing the adjustment of the machine, as will be readily understood, said dogs 100 therefore simply serving the function of checks to hold the drum to its adjustment. 85

In the use of the machine to provide for a positive and even movement thereof it is found desirable to employ a plurality of the propelling devices just described, and in the drawings are illustrated three of such devices at the rear side of the machine. The central 100 one of the propelling devices has already been particularly described, but the other propelling devices, respectively above and below the central propelling device and designated by the numerals 91^a and 91^b, respectively, are 105 duplicates in construction of each other and of the said central device, excepting that the said upper and lower propelling devices are not provided with the construction for regulating the size of the mesh, this construction 110 only being necessary with one of the propelling devices. The said upper and lower propelling devices are adjustably clamped onto the frame-board substantially in the manner already described, but the operating-levers 115 107^a thereof are shorter than the hand-lever 107 and are connected to each other and with said hand-lever 107 by a single continuous connecting-bar 115, provided with a series of perforations 116, adapted to receive the pivot-pins 117 of the levers 107 and 107^a according 120 to the adjusted position of the propelling devices at the rear side of the machine.

By reason of the use of a connecting-bar 115 the manipulation of the hand-lever 107 of the central propelling device provides for the simultaneous operation of all of the propelling devices, so that the machine will be evenly moved along as the weaving progresses, it being noted at this point that the warp or line 130 wires are stretched to a tight tension and by having one or more tight wraps around the ro-

tating drums of the propelling devices causes the said drums to move along the wires by reason of frictional engagement therewith.

The provision of the finger-pins 108 is important in connection with the propelling devices above and below the central propelling device—as, for instance, the lower propelling device might feed along the wire a trifle faster than the upper propelling device and thereby tend to produce an uneven mesh. Should this occur, the finger-pins 108 of the lower propelling device would be grasped, so as to disengage the adjusting-dog 103 from the drum of said lower propelling device, so that said lower propelling device would not operate until the upper propelling device had been moved along sufficiently to correct the uneven feeding, after which the adjusting-dogs of the lower propelling device will be allowed to again engage with the ratchet-teeth of the rotating drum.

Modifications of the machine might be observed, such as illustrated in Fig. 27 of the drawings, in which figure is illustrated a modification of the stationary spindles for the twister-wheels. In this modified construction the spindle 11^a is illustrated as being sufficiently large to receive therein a barbed line-wire should wire of this character be used in weaving the fabric, and said spindle is also closed throughout its entire length, so as to leave no edges to be engaged by the barbs or wire, and at one end the spindle has detachably fitted thereon a flared mouthpiece 11^b, which serves as a guide for the barbed wire to prevent its catching on the end of the spindle which moves along such wire.

Other modifications of the machine may be observed and various changes in the form, proportion, and the minor details of construction may be resorted to without departing from the principle or sacrificing any of the advantages of this invention.

Having thus described the invention, what is claimed, and desired to be secured by Letters Patent, is—

1. In a wire-fabric machine, a series of intermeshing cogged twister-wheels provided at diametrically opposite points with peripheral notches, each notch being formed by the space between a pair of cogs, spool-carriers engaging with the notches of said wheels, stationary circular guides arranged concentric with and adjacent to the peripheries of the wheels in the vertical plane thereof to hold the spool-carriers in engagement therewith, and automatically-operating switches for transferring the spool-carriers from one twister-wheel to the adjacent wheels, substantially as set forth.
2. In a wire-fabric machine, an alined series of cogged twister-wheels provided at diametrically opposite points with peripheral notches, each notch being formed by the space between a pair of cogs, spool-carriers adapted to engage with the peripheral notches of said wheels, stationary circular guides arranged concentric with and adjacent to the periph-

eries of the wheels to hold the spool-carriers in engagement therewith, and means for automatically deflecting the spool-carriers from the guides of one wheel to the guides of an adjacent wheel, substantially as set forth.

3. In a wire-fabric machine, a series of alined intermeshing cogged twister-wheels provided with diametrically opposite peripheral notches, each notch being formed by the space between a pair of cogs, spool-carriers adapted to engage with said notches, and automatically-operated diagonally opposite switch-points for transferring the spool-carriers from one twister-wheel to the adjacent wheels for rotation with the latter, substantially as set forth.

4. In a wire-fabric machine, a series of intermeshing cogged twister-wheels provided at diametrically opposite points with peripheral notches, spool-carriers engaging with the notches of said wheels, circular guides arranged adjacent to the peripheries of the wheels, switch points or fingers arranged at diagonally opposite points and at opposite sides of each twister-wheel, and means for automatically adjusting said switch-points to deflect the spool-carriers from the guides of one wheel to the guides of the adjacent wheels, substantially as set forth.

5. In a wire-fabric machine, an upright frame-board provided with a series of vertically-aligned openings, hollow stationary spindles detachably clamped at one end in the openings of the frame-board, a series of intermeshing cogged twister-wheels loosely mounted on said stationary spindles at one side of the frame-board, spool-carriers mounted on the wheels, and transferring mechanism for the spool-carriers, substantially as set forth.

6. In a wire-fabric machine, the combination of an upright frame-board provided with a series of vertically-aligned openings, hollow stationary spindles fitted at one end in said openings and provided in opposite sides near one end with diametrically opposite notches, open locking-keys wedged into said notches to detachably fasten the spindles in place, a series of intermeshing cogged twister-wheels mounted on said spindles, spool-carriers mounted on the wheels, and transferring mechanism for the spool-carriers, substantially as set forth.

7. In a wire-fabric machine, an upright frame-board provided with a series of vertically-aligned openings, hollow stationary spindles fitted at one end in said openings and provided in opposite sides near one end with diametrically opposite notches, said spindles being further provided intermediate of their ends at one side of the frame-board with annular bearing-shoulders, detachable bearing-bushings loosely fitted on said spindles at one side of said bearing-shoulders and provided at their ends opposite the bearing-shoulders with annular bearing-flanges resting flat against one side of the frame-board, a series

of intermeshing cogged twister-wheels having cylindrical flanged hubs loosely turning on said bearing-bushings, and a trifle shorter in length than the distance between the flanges 5 of said bushings and the shoulders of the spindles, wedge locking-keys adapted to fit over one end of the spindles and provided with opposite parallel portions engaging in the opposite side notches of the spindles, the 10 spool-carriers, and transferring mechanism for the carriers, substantially as set forth.

8. In a wire-fabric machine, an upright frame-board, a series of hollow vertically-alined spindles fitted at one end in said board, 15 combined guide and supporting disks loosely mounted on the outer end of said spindles, a series of intermeshing cogged twister-wheels mounted on the spindles and having diametrically opposite peripheral notches, spool-carriers having neck-pieces engaging in the 20 notches of said wheels and at their ends opposite the neck-pieces with circular bearing-heads having a peripheral contact with said combined guide and supporting disks at the 25 outer ends of the spindles, and suitable transferring mechanism for the spool-carriers, substantially as set forth.

9. In a wire-fabric machine, the upright frame-board, a series of hollow vertically-alined spindles fitted at one end in said board, 30 combined guide and supporting disks having central bearing-collars having an interlocking connection with the outer ends of the spindles and loosely turning thereon, said 35 disks being open at the center for the passage of the warp or line wires, a series of intermeshing cogged twister-wheels mounted on the spindles directly adjacent to one side of the frame-board, spool-carriers provided at 40 one end with neck-pieces registering with the notches of the twister-wheels and at their opposite ends with circular bearing-heads provided with a series of wire-guide openings and having a peripheral contact with said 45 combined guide and supporting disks and spool-carrier transferring mechanism, substantially as set forth.

10. In a wire-fabric machine, an upright frame-board, a series of hollow vertically-alined spindles fitted at one end in said board, 50 combined guide and supporting disks mounted to loosely rotate on the outer ends of said spindles, a series of intermeshing cogged twister-wheels mounted on the spindles directly adjacent to one side of the frame-board, 55 spool-carriers engaging with the twister-wheels at one end and provided at their opposite ends with circular bearing-heads peripherally contacting with said combined guide 60 and supporting disks and having a plurality of separate guide-openings for the weft or mesh wire wound on the spools of the carrier, and suitable shifting mechanism for the carriers, substantially as set forth.

65 11. In a wire-fabric machine, an upright frame-board, a series of hollow vertically-alined spindles fitted at one end in said boards,

combined guide and supporting disks mounted for a loose rotation on the outer ends of said spindles, a series of intermeshing cogged 70 twister-wheels mounted on the spindles directly adjacent to one side of the frame-board, spool-carriers essentially comprising a substantially U-shaped frame-arm provided at a point intermediate of its ends with an 75 offstanding spool-axe, with a neck-piece at one end for engagement with the twister-wheels, and at its opposite end with a circular bearing-head having a plurality of wire-guide openings and working on the periphery 80 of the combined guide and supporting disks, wire-spools loosely mounted on the axles of the spool-carriers, combined tension and locking springs detachably fitted on said axles and bearing against one side of the spools, 85 and suitable transferring mechanism for the spool-carriers, substantially as set forth.

12. A spool-carrier, for machines of the class described, essentially comprising a frame-arm having an offstanding spool-axe 90 provided at one end with a squared locking-head and short locking-studs projected from diametrically opposite sides of said head, a wire-spool arranged to turn on said axle, and a longitudinally-bowed spring-tension 95 and locking plate adapted to bear at its ends against one of the heads of the wire-spool and provided intermediate of its ends with a central squared opening and guide-notches communicating with the opening at opposite 100 side edges thereof, said plate being adapted to be turned to a position to bring said guide-notches in and out of alinement with said locking-studs, said squared opening engaging with the locking-head when said notches are 105 turned at right angles to the locking-studs, substantially as set forth.

13. In a wire-fabric machine, a series of intermeshing cogged twister-wheels provided at diametrically opposite points with peripheral notches, circular guides arranged adjacent to the peripheries of the wheels, spool-carriers provided at one end with a pair of spaced retaining-plates receiving therebetween the cogged peripheries of the wheels 115 and said circular guides, and means for shifting the spool-carriers from the guides of one wheel to the guides of the adjacent wheels, substantially as set forth.

14. In a wire-fabric machine, a series of 120 intermeshing cogged twister-wheels provided at diametrically opposite points with peripheral notches, circular guides arranged adjacent to the peripheries of the wheels, spool-carriers provided at one end with short neck-pieces engaging said notches and with a pair of spaced retaining-plates respectively disposed at opposite sides of the cogged peripheries of the wheels and said circular guides, 125 and means for shifting the spool-carriers 130 from the guides of one wheel to the guides of the adjacent wheels, substantially as set forth.

15. In a wire-fabric machine, a series of in-

termeshing cogged twister-wheels provided at diametrically opposite points with peripheral notches, circular guides arranged adjacent to the peripheries of the wheels, spool-carriers 5 provided at one end with a pair of parallel elliptical retaining-plates respectively disposed at opposite sides of the peripheries of the wheels and said circular guides, and with a short rounded neck-piece connecting said 10 retaining-plates and registering in the notches of the twister-wheels, and means for deflecting the elliptical retaining-plates of the spool-carriers from the guides of one wheel to the guides of the adjacent wheels, substantially as set forth.

16. In a wire-fabric machine, a series of intermeshing cogged twister-wheels, V-shaped guide plates or castings arranged at opposite sides of the series of wheels with their apices 20 or points projected into the reentrant spaces between the meshing faces of the wheels, said V-shaped guide plates or castings having segmental side portions arranged in the same circular plane as the segmental side portions of 25 the adjacent guide plates or castings, spool-carriers provided at one end with a pair of spaced elliptical retaining-plates respectively disposed at opposite sides of the peripheries of the wheels and said circular guide plates 30 or castings, and means for deflecting the elliptical retaining-plates of the spool-carriers from the guides of one wheel to the guides of the adjacent wheel, substantially as set forth.

17. In a wire-fabric machine, a series of intermeshing vertically-aligned cogged twister-wheels provided with diametrically opposite peripheral notches, V-shaped guide plates or castings arranged at opposite sides of the series of wheels and projecting into the spaces 40 between the meshing faces of the wheels, said V-shaped guide plates or castings having segmental side portions and essentially comprising an outer base-flange and a main guide-flange projected from the inner side of the 45 base-flange intermediate of its edges and at right angles thereto, said main guide-flanges being provided with a flat bearing-surface arranged parallel with the main base-flange, spool-carriers provided at one end with a pair 50 of parallel elliptical retaining-plates respectively disposed at opposite sides of the main guide-flanges of said guide plates or castings, the outer edges of the elliptical plates riding in contact with the outer base-flanges at opposite sides of said main guide-flanges, said 55 spool-carriers being further provided with short neck-pieces connecting the retaining-plates, registering in the notches of the twister-wheels, and riding in contact with the flat bearing-surfaces at the inner edges of the main 60 guide-flanges, and means for deflecting the elliptical retaining-plates of the spool-carriers from the guides of one wheel to the guides of the adjacent wheels, substantially as set forth.

18. In a wire-fabric machine, a series of intermeshing vertically-aligned cogged twister-

wheels provided with diametrically opposite peripheral notches, V-shaped guide plates or castings arranged at the opposite sides of the 70 series of wheels and projecting into the spaces between the meshing faces of the wheels, spool-carriers provided at one end with a pair of parallel elliptical retaining-plates respectively disposed at the opposite sides of the 75 peripheries of the wheels and said guide plates or castings, and with a short rounded neck-piece connecting said retaining-plates and registering in the notches of the twister-wheels, switch points or fingers arranged at 80 diagonally opposite sides of each twister-wheel, and means for adjusting said switch-points to deflect the elliptical retaining-plates of the spool-carriers from the guides of one wheel to the guides of the adjacent wheels, 85 substantially as set forth.

19. In a wire-fabric machine, a series of intermeshing vertically-aligned cogged twister-wheels provided with diametrically opposite peripheral notches and on their front sides 90 with circular guide-flanges, circularly-aligned guides arranged adjacent to the peripheries of the wheels, and projecting into the spaces between the meshing faces thereof, spool-carriers provided at one end with a pair of elliptical retaining-plates respectively disposed at 95 opposite sides of said guides, and with a short rounded neck-piece connecting said retaining-plates and registering in the notches of the twister-wheels, oscillatory switch points 100 or fingers arranged at diagonally opposite sides of each twister-wheel, and means for adjusting the free ends of the switch-points against the circular guide-flanges of the twister to deflect the elliptical retaining-plates 105 of the spool-carriers from the guides of one wheel to the guides of the adjacent wheels, substantially as set forth.

20. In a wire-fabric machine, a series of intermeshing vertically-aligned cogged twister-wheels provided with diametrically opposite peripheral notches and front circular guide-flanges, V-shaped guide plates or castings arranged at opposite sides of the series of 110 wheels and projecting into the spaces between the meshing faces thereof, said V-shaped guide plates or castings having segmental side portions arranged in the same circular plane as the corresponding portions of the adjacent guide plates or castings, spool-carriers provided at one end with neck-pieces 115 engaging the notches of the wheels and with a pair of elliptical retaining-plates respectively disposed at opposite sides of the guide plates or castings, oscillatory switch points 120 or fingers pivotally mounted at one end on every alternate guide plate or casting, in each vertical row of such plates or castings, so as to dispose a pair of switch points or fingers at diagonally opposite sides of each twister-wheel, a pair of vertically-reciprocating operating-bars respectively connecting with all of 125 the switch points or fingers in each vertical row, a link connection between adjacent ends 130

of said operating-bars to provide for a simultaneous movement thereof in opposite directions, and a cam device actuated by one of the twister-wheels and engaging with one of the operating-bars to provide for the simultaneous operation of all of the switch points or fingers, substantially as set forth.

21. In a wire-fabric machine, a series of intermeshing cogged twister-wheels one of which wheels carries adjusting-pins, circular guides arranged adjacent to the peripheries of the wheels, spool-carriers engaging with the wheels and having at one end a pair of retaining-plates respectively disposed at opposite sides of the circular guides, inwardly-projecting switch points or fingers pivotally mounted at their outer ends beyond diagonally opposite sides of each twister-wheel, a pair of vertically-reciprocating operating-bars respectively having a pin connection with all of the switch points or fingers in each vertical row, an oscillating-link connection between the adjacent ends of said oscillating bars to provide for a simultaneous movement thereof in opposite directions, a rectangular yoke fitted on one of the operating-bars, and a toothed cam-wheel engaged by the adjusting-pins of one of the twister-wheels and carrying at one side a cam projection working within said yoke to provide for the adjustment of said operating-bars simultaneously in opposite directions, substantially as set forth.

22. In a wire-fabric machine, an upright frame-board, a series of intermeshing cogged twister-wheels, one of which wheels carries on its inner side a pair of spaced adjusting-pins, circular guides arranged adjacent to the peripheries of the wheels, spool-carriers engaging with the wheels and having at one end a pair of retaining-plates respectively disposed at opposite sides of the circular guides, inwardly-projecting switch points or fingers pivotally supported at their outer ends beyond diagonally opposite sides of each twister-wheel and working over the reentrant portions of the guides between the meshing faces of the wheels, a pair of vertically-reciprocating operating-bars respectively connected with all of the switch points or fingers in each vertical row thereof, an oscillating-link connection between the adjacent ends of said bars, a rectangular yoke fitted on the inner side of one of the operating-bars and provided with straight upper and lower sides and opposite curved end portions, a short stub-shaft mounted in the frame-board and carrying at its inner end a toothed cam-wheel engaged by the adjusting-pins of one of the twister-wheels and carrying at one side a cam projection having a single eccentrically-disposed contact-point and a curved bearing portion concentric with the cam-wheel, a dial-plate mounted on one side of the frame-board, a pointer fitted on the outer end of the stub-shaft and working over the dial-plate, and a

spring arranged at the inner side of said cam-wheel, substantially as set forth.

23. In a wire-fabric machine, the combination of a series of intermeshing cogged twister-wheels, spool-carriers engaging with the twister-wheels, circular guides for retaining the carriers in engagement with the wheels, a series of movable switch points or fingers working between the wheels to deflect the carriers from the guides of one wheel to the guides of the adjacent wheels, a single operating-bar connecting said switch points or fingers and carrying a rectangular yoke, an automatically-rotated cam-wheel carrying at one side a cam projection working in said yoke and providing for the intermediate elevation and depression thereof, substantially as set forth.

24. In a wire-fabric machine, the combination with the wheeled upright frame carrying weaving mechanism, of a propelling device having a suitably-rotated drum receiving on its periphery a tight wrap of a warp or line wire of the fabric, and a clamp carrying said drum and adjustably fitted to the frame to provide for the vertical adjustment of the former, substantially as set forth.

25. In a wire-fabric machine, the combination with the wheeled upright frame carrying weaving mechanism, of a propelling device suitably connected with the frame and having a rotatable drum frictionally engaging with a warp or line wire of the fabric, and a device for regulating the limit of movement of the drum to provide for a corresponding regulation of the length of mesh of the fabric, substantially as set forth.

26. In a wire-fabric machine, the combination with the wheeled upright frame carrying weaving mechanism, of a propelling device comprising a pair of angled clamp-plates adjustably embracing opposite side edges of the upright frame, a rotating drum journaled between said clamp-plates and having a peripheral wire-groove adapted to receive a tight wrap of a warp or line wire of the fabric, a device for regulating the limit of movement of said drum, and lever-operated ratchet mechanism for positively rotating the drum in one direction, substantially as set forth.

27. In a wire-fabric machine, the combination with the wheeled upright frame carrying weaving mechanism, of a propelling device comprising a pair of angled clamp-plates adjustably embracing opposite side edges of the frame, a rotating drum provided with oppositely-disposed spindle projections journaled in said clamp-plates, and opposite internally-toothed ratchet-flanges, said drum being adapted to receive a tight wrap of a warp or line wire of the fabric, fixedly-positioned check-dogs arranged at one side of the drum and engaging with the teeth of one of the ratchet-flanges thereof, and a lever pivotally supported on one of the spindle projections and carrying a pair of adjusting-dogs ar-

ranged at the opposite side of the drum and engaging with the teeth of the other ratchet-flange thereof, substantially as set forth.

28. In a wire-fabric machine, the combination with the upright frame carrying weaving mechanism, of a propelling device comprising a pair of angled clamp-plates adjustably embracing opposite side edges of the frame, a rotating drum provided with oppositely-disposed spindle projections journaled in said clamp-plates and opposite internally-toothed ratchet-flanges, said drum being adapted to receive a tight wrap of the warp or line wire of the fabric, a pair of fixedly-positioned check-dogs mounted at the inner side of one of the clamp-plates for engagement with the teeth of one of the ratchet-flanges of the drum, and a hand-lever carrying at one end a movable cap-plate turning on one of the spindle projections of the drum and provided with oppositely-located segmental slots, a pair of adjusting-dogs pivotally mounted at the inner side of said movable cap-plate and adapted to engage with the teeth of the other ratchet-flange of the drum, said adjusting-dogs being provided at one side of their pivotal support with finger-pins projecting through said segmental slots, substantially as set forth.

29. In a wire-fabric machine, the combination with the upright frame carrying weaving mechanism, of a propelling device comprising a pair of angled clamp-plates embracing opposite side edges of the frame, one of said clamp-plates being provided with vertically-aligned diametrically opposite limiting-pins and a circular series of pin-openings, an adjustable stop-pin adapted to be fitted in any of the series of pin-openings, a rotating drum provided with oppositely-disposed spindle projections journaled in said clamp-plates and an internally-toothed ratchet-flange, and a hand-lever pivotally supported on one of the spindle projections and carrying a pair of adjusting-dogs engaging the teeth of said ratchet-flange to provide for the rotation of said drum, said lever being provided at one side adjacent to

its pivotal support with a web or lug adapted to engage said adjustable stop-pin and also said limiting-pins, substantially as set forth.

30. In a wire-fabric machine, the combination with the upright frame carrying weaving mechanism; of a plurality of independently vertically adjustable propelling devices clamped onto the frame at different points, and a single operating connection between said propelling devices to provide for the simultaneous operation thereof, said propelling devices having a frictional engagement with the warp or line wires of the fabric being woven, substantially as set forth.

31. In a wire-fabric machine, the combination with the upright frame carrying weaving mechanism; a plurality of duplicate propelling devices adjustably clamped on the frame at different points, said propelling devices having ratchet-rotated drums receiving a tight wrap of the warp or line wires and operating-levers for turning said drums, the operating-lever of one of the propelling devices being elongated to provide a hand-grasp, and a single continuous connecting-bar pivotally connecting the operating-levers of said propelling devices, substantially as set forth.

32. In a wire-fabric machine, the combination with the upright frame carrying weaving mechanism, of a propelling device suitably connected with the frame and having a single rotatable drum adapted to receive on its periphery a complete convolution or wrap of the line-wire whereby the wire has a frictional bearing on the entire circumference or periphery of the drum to provide the necessary frictional grip between the drum and the wire, substantially as set forth.

In testimony that I claim the foregoing as my own I have hereto affixed my signature in the presence of two witnesses.

ALVA L. KITSELMAN.

Witnesses:

JOHN H. SIGGERS,
HAROLD H. SIMMS.
